[57] ABSTRACT

A length of stretch fabric which is readily selectively engaged with a wristwatch and held, by a clip or the like, by its likewise free ends in a closed loop so as to effectively function as a watchband. The fabric is selected to coordinate with the wearer's attire and the stretch thereof facilitates placement and removal of the band from about the wearer's wrist.

A REPLACEABLE WATCHBAND

The present invention relates generally to watchbands, and more particularly to an improved watchband fabricated of stretch fabric.

It is desirable to have a watchband that is fashion-coordinated with the wearer's attire, and this is best achieved using stretch fabric since this material is readily printed and otherwise embodied with a pleasing decorative design. The popularity of stretch fabric as a watchband has not reached its ultimate potential, however, because it is not also readily replaceable so that the wearer has a range of selection in much the same way as with other items of apparel.

Broadly, it is an object to provide an improved stretch fabric watchband overcoming the foregoing and other shortcomings of the prior art. Specifically, it is an object to provide a readily replaceable watchband and in so doing thus afford the wearer a greater choice of bands for the purpose of fashion coordination.

A replaceable watchband exemplifying the present invention includes a selected length of stretch fabric that after being engaged to a wristwatch is selectively held by a clip or the like in a closed loop so as to function as a watchband. The clip is opened only during replacement of the band since removal from the wearer's wrist is achieved by stretching the band.

The above brief description, as well as further objects, features and advantages of the present invention, will be more fully appreciated by reference to the following detailed description of a presently preferred, but nonetheless illustrative embodiment in accordance with the present invention, when taken in conjunction with the accompanying drawings, wherein:

FIG. 1 is a front perspective view of the replaceable watchband hereof;

FIG. 2 is a rear perspective view thereof; and

FIG. 3 is a partial perspective view, on an enlarged scale, illustrating structural details of a holding member of the band.

Reference is now made to the drawings wherein there is shown a replaceable watchband, generally designated 10, demonstrating objects and advantages of the present invention. As illustrated in the drawings, band 10 is fabricated of a stretchable material, preferably a stretch fabric of uniform thickness consisting wholly or in part of elastomeric material, such as is used in foundation garments.

In accordance with the present invention, the elongated stretch fabric band 10 has an outer visible surface 12 which will be understood to be appropriately decorated, as by being printed or otherwise embodied with a design or colors, which advantageously can be fashion-coordinated with the user's attire. In this regard, it is contemplated that band 10 will be one of plural bands made available to the user from which she can make a selection depending upon her attire at the time. The foregoing thus necessitates that band 10 be readily attachable and detachable from a conventional wristwatch 12 to permit the replacement thereof.

As is perhaps best seen in FIG. 2, the wristwatch 14 includes band-retaining bars 16 and 18 for threadably receiving the band 10 and completing the engage-

ment of the watch 14 to the band. Specifically, it is contemplated, in accordance with the present invention, that the stretch fabric band 10 will be provided in a selected length which terminates in opposite free ends 20 and 22, as clearly illustrated in FIG. 3, and that one of these free ends will be threaded through the slots bounded by the bars 16, 18. Co-operating to thereafter hold these free ends 20 and 22 in a closed loop, such as is illustrated in FIGS. 1 and 2, is holding means 24.

Holding means 24 includes a substantially flat body 26 which at opposite ends has a first and second rearwardly bent pair of ears 28 and 30. Pivotally mounted, as at 32, in each of the ears are L-shaped gripping members 34 and 36. As is clearly illustrated in FIG. 3, each of the gripping members, as exemplified by the gripping member 34, is adapted to be pivoted from a clearance position out of engagement with its cooperating band end 20 through closing movement 38 into engagement with said band end. To contribute to establishing a firm engagement therebetween, the shorter leg 40 of each of the gripping members 34, 36 has an interrupted gripping edge 42 which, when pressed into the body of the band 10, is effective in firmly engaging the same. Moreover, it will be understood that the band 10 will be under a slight tension in the opposite directions 44, as illustrated in FIG. 3, which is effective in holding the gripping members 34 and 36 in their respective closed positions in engagement with the band free ends 20 and 22.

From the foregoing it should be readily appreciated that with the band free ends 20 and 22 engaged within the holding means 24 that the band 10 forms a closed loop which permits the same to efficiently function as a watchband in that the user can slip her or his wrist through the opening bounded by the closed loop band 10. Naturally, the placement of band 10 upon the wearer's wrist and also the removal thereof is facilitated by the stretch capacity of the band 10. That is, the band has a minimum size diameter, as illustrated in FIGS. 1 and 2, that will be understood to be related to the wearer's wrist and is adapted, by stretching, to be increased from this minimum size to an appropriately increased size which readily permits removal of the band 10.

From the foregoing it should also be readily appreciated that simply by pivoting the gripping members 34 and 36 through opening movement that holding means 24 is readily detached from the band free ends 20 and 22. Once this is achieved, the band 10 is itself readily detached from its threaded engagement with the wristwatch 14. The user can then simply rethread another replaceable watchband, similar to the band 10 but with perhaps another design or color embodied therein, about the bars 16 and 18, thereby engaging the watch 14 intermediate the free ends of this new band. These free ends are then engaged, in the manner already described, so as to form the band 10 into a closed loop which permits the use thereof as a watchband.

A latitude of modification, change and substitution is intended in the foregoing disclosure and in some instances some features of the invention will be employed without a corresponding use of other features. Accordingly, it is appropriate that the

appended claims be construed broadly and in a manner consistent with the spirit and scope of the invention herein.

I claim:

1. A replaceable watchband comprising, in combination, a wristwatch having bar means respectively bounding watchband-receiving loops at opposite sides thereof, a watchband formed of an elongated length of stretch fabric of substantially uniform thickness having a medial length portion terminating in opposite free ends, said watchband being operatively arranged with said medial length portion thereof replaceably threaded through said loops in underlying relation to said wristwatch and with said free ends in a remote position from said loops and in unattached relation thereto, and a holding means operatively effective to receive said band free ends from opposite directions so as to form a closed loop of

said band with said holding means located in opposing relation to said wristwatch, said holding means including a substantially flat body and a pair of L-shaped gripping members relatively spaced from each other on and pivotally mounted to said body, each said gripping member having a short leg including gripping means thereon and a long leg for finger pivotal movement of said short leg, and a band-receiving passage between each said short leg and flat body to receive a cooperating one of said band free ends therein so as to be engaged by the pivoting of said short leg to secure the same to said holding means to thereby form said watchband closed loop, whereby said wristwatch is removable from the user's wrist by expansion of said band, and said band is readily detachable from said holding means preparatory to the replacement thereof.
